PROCESS OF PRODUCING DECORATIVE
SHEET MATERIALJames J. Jackson, Woodbury, N. J., assignor to
Sandura Company, Inc., Philadelphia, Pa., a
corporation of New Jersey

Application March 2, 1933, Serial No. 659,433

21 Claims. (Cl. 91—68)

This invention relates to decorative wear coverings for floors or other surfaces and to a method of preparing such coverings.

The improvement relates generally to so called "smooth surface" coverings known to the trade and public as equivalents of or improvements for linoleum and painted coverings of either the cloth or felt-backed type.

The present invention includes a method of 10 treating fibrous sheet material to obtain an improved, finished, decorative product having remarkable flexibility, and toughness, and having clean-cut and well-defined decorations substantially throughout the thickness of the sheet. Coloring material is applied in such a manner as to obtain greater penetration of decorative material than could be heretofore obtained for practical purposes.

In a preferred manner of conducting the present process, a backing composition comprising for 20 instance oil or lacquer or both, is first applied to one side of a fibrous sheet, and thereafter decorative material is applied to the other side. The amounts of materials and the interval permitted 25 between the application of the materials to the two sides of the sheet are so controlled that the materials penetrating from both sides, preferably overlap within the body of the sheet. By this means, strength of the finished product is assured and splitting of the sheet into layers after 30 drying is prevented.

By way of illustration, reference is made to the accompanying drawings, in which:

Fig. 1 is a vertical sectional view of apparatus shown more or less diagrammatically and in a preferred arrangement;

Figs. 2 to 5 are cross sectional views of the product in various stages of the process;

Fig. 6 is a top view of the product shown in cross section in Fig. 5; and

Fig. 7 is a vertical sectional view of a portion of apparatus employed in a modified arrangement of the apparatus shown in Fig. 1.

The apparatus shown in Fig. 1 comprises a support 1 on which is mounted a roll of the fibrous sheet material 2, a trough 3 for holding material to be applied to one side of the sheet 2, and a print machine 4 for applying decorative coloring material to the opposite side of the sheet 2. The sheet 2 passes between rolls 5 and 6, the latter being adapted to apply backing material 7 from the trough 3 to one side of the sheet 2. A doctor blade 8 is positioned adjacent the roll 6 and is adapted to vary the amount of material applied

to the sheet by swinging the blade on its hinge 9 toward or away from the roll 6.

The roll 6 may be a roll having minute grooves, such as an engraving surface, cut in its surface or it may be a smooth-surfaced metal, rubber or 5 felt roll. The type of roll used depends to some extent on the composition or viscosity of the material applied to the sheet and also on the amount of a given composition to be applied per unit area of sheet material.

The sheet passes from between the rolls 5 and 6 over a driven roll 10 and then to the print machine 4. Rolls 5 and 6 are driven to draw the sheet material from its original roll on the support 1. The roll 10 is raised sufficiently above 10 the floor or the base of the print machine to provide for a proper drying interval and also to provide for a predetermined slack in the sheet material ahead of the print machine 4. The roll 10 is also preferably of large diameter so as not 15 to bend the sheet too sharply, and to provide for proper control of the longitudinal movement of the sheet in accordance with the rate of passage 20 of the sheet through the print machine.

In the operation of the apparatus just described, oil or lacquer or other materials mentioned herein are applied to one side of the fibrous sheet 2 by the roll 6, in an amount which penetrates uniformly into the sheet and preferably 25 only part of the way through the body thereof. 30 The individual fibres are coated and the backing materials preferably do not fill the voids between the fibres. The sheet 2 is drawn over the roll 10 and a slack is preferably provided in the sheet 35 between this roll and the print machine 4 to take care of differences in speeds, if any, in the backing 40 applying machine and in the print machine 4. The intermittent action of the latter machine is an important factor that must be taken into account. The sheet is moved through the print 45 machine with a step by step motion and during the momentary periods of rest the desired design units are applied. The sheet must therefore not be drawn at too high a rate through the 50 backing applying means lest the slack should become too great.

Also just enough excess sheet material should be maintained at all times between the roll 10 and the print machine 4 to prevent the sheet from 55 being taut at any time during the operation of the latter. A pronounced dip in the sheet is formed to provide this slack. Thus a ready supply of sheet material is easily drawn from and is always available to take care of variations of 55

speed that usually occur in operating the print machine.

The dip or bend in the sheet material between the roll 10 and the end of the print machine 4 5 may, if desired, be more pronounced in proportion to that shown in Fig. 1. For quick drying backing material the length of the sheet material in the dip or bend may be less than for slow drying backing compositions. Also, the distance 10 between the roll 10 and the end of machine 4 may be increased or decreased depending on the slow or rapid drying features of the backing material. By way of example, in employing backing materials of the type to be more specifically 15 described below, it has been found that satisfactory results are obtained by having an average length of about thirteen feet of sheet material in the dip and a horizontal distance of about seven and one-half feet between the center line of the roll 10 20 and the rear end of the print machine 4.

By maintaining a proper amount of slack in the fibrous sheet, the under side of the sheet to which the backing material is applied is somewhat stretched and the pores are opened, without 25 undue strain on the fibres, to insure more rapid drying before the sheet reaches the print machine for application of decorative material to the upper surface of the sheet.

The decorated sheet passes from the print 30 machine 4 to various other units for further treatment, if desired. For instance, the sheet may be dried in a drying room, and after passing it through a drying room it may be passed through a saturant bath to render the finished product 35 hard and wear resistant, in the manner set forth in my copending application Serial No. 659,434 filed March 2, 1933.

The present process is illustrated diagrammatically in Figs. 2 to 6 in the accompanying drawings. Fig. 2 illustrates the first stage in which one side of the fibrous sheet 2 is treated with backing material in such amount as will penetrate part of the way through the body of the sheet to provide a backing layer 11. Figs. 3 to 6 represent 40 the second stage of the process in which decorative material is applied to the opposite side of the said sheet as indicated by the diagonal color lines 12. In Fig. 4 a different color, as represented by the vertical lines 13 has been applied. Decorative coloring material may be applied solidly 45 throughout as in the case of the light green color in Fig. 3 and the pink or red color in Fig. 4, or the decorative coloring material may be applied in patterns, as illustrated in Figs. 5 and 6 in which 50 the portions 14 represent blue and the portions 15 represent red, thus simulating a tile effect. In lieu of these geometrical figures illustrated in the drawings, the decorations may be of any shape or style. In the present process, designs of startling 55 intricacy are applicable, and with the result that the patterns are clearly distinguishable whether the finished product be subjected to wear or not, as the case may be.

There is no limitation as to the variety of color 60 shades, light or dark, that may be reproduced in a particular sheet except that in the case of fibrous sheet material which is originally dark, it is generally difficult to reproduce certain colors exactly.

The print paints, inks, or dyes are applied in 65 such an amount as to penetrate well into the body of a fibrous sheet or substantially through the same. It is important to have the print paint and the backing material at least meet within the 70 sheet or preferably overlap as shown at 16 in

Fig. 4. In the latter instance there is a mechanical interlocking which takes place when the print paint and the backing material are dried in the sheet. By this interlocking the sheet is strengthened and splitting thereof into layers is prevented. 5

As shown in Fig. 7, one or more festoons in the sheet material may, if desired in certain cases, be formed between the backing machine and the print machine as for instance between the roll 10 and the print machine 4 as shown in Fig. 1. 10 The festoons may be subjected to drying conditions in any well known manner. The sheet between the roll 11 at the end of the festoon arrangement and the print machine 4 is provided with a pronounced dip for the reasons above stated. 15

Although drying of the backing material has been specified, the sheet may be passed from the backing machine to the print machine, and coloring applied without completely drying the sheet before decorating it. 20

Various types of fibrous materials may be employed in the present process but a type of fibrous sheet which is particularly adapted to the present invention is a new type of sheet known as "Krafelt". The nature of this material and the 25 method of manufacturing it, is set forth in detail in recent patents and in copending applications of Ralph G. Jackson, Serial No. 541,668, filed June 2, 1931 (now patent No. 1,998,779) and Serial No. 634,057, filed September 20, 1932 (now 30 Patent 1,998,780). This new type of felt sheet is peculiar in that it has what may be defined as curled or kinky vegetable fibers of wood pulp or other cellulose fibers.

One characteristic appearance of the floor 35 coverings made by the present invention from the curly fibre type of sheet is the obtainable velvety texture of the surface which has an actual nap surface unless lacquered or varnished. It has been found that the final decorated and 40 completed product is wear resisting, and will wear smoothly and uniformly with even texture and is highly resistant to tearing strains.

Two outstanding characteristics of the felted 45 pulp fibres are the curled condition of the fibres and the swelling of the fibres. Due to the fact that the fibres are swollen, they make a more open felt than previously known, also color materials such as paints and dyes penetrate better than they do in providing similar treatment to 50 other sheets, and also due to the fact that the fibres are curled and hooked and matted together, the coloring materials, although they follow the fibre, do not spread out laterally so far as they would on fibrous material heretofore known, but on the other hand penetrate inwardly as rapidly and deeply as they extend laterally. For this reason, more definite lines may be 55 formed in the resultant product by printing or otherwise applying decorations. The printed or 60 colored lines are smoother on the edges due to the fact that the fibres are kinky and curly and do not extend in any particular direction in the sheet. Due to the shape of each fibre and the 65 consequent interlocking of the fibres, a sheet of unusual strength is obtained. In this type of sheet, the surface may be roughened, that is, the nap may be raised, mechanically, after the sheet has been made. Due to the formation of the sheet, the fibres after being raised are hooked and matted together and do not loosen in such a way that they might tend to be lost from the 70 sheet.

Although the particular sheet referred to above 75 has the property of absorbing liquid materials

rapidly and of carrying coloring materials directly inwardly without spreading laterally to as great an extent as in the case of ordinary felt, the present process makes it possible to permit 5 the print paints to penetrate more uniformly, and more quickly. Also by applying backing material and print paints to opposite sides of the sheets, the colorings penetrate farther. A thicker sheet can be used than otherwise and yet it will be of 10 sufficient flexibility. The goods can be wetted from the back with oil, to make up for the deficiency of oil in the goods when it is desirable to put less oil in the goods from the face by means of print paints for instance.

15 The backing material may be a pigmented or clear oil or lacquer. An example of a highly desirable oil backing material is as follows:

Bodied linseed oil with driers about 50 parts by weight, and petroleum benzene of a grade 20 somewhat less refined than gasoline, about 50 parts by weight.

An example of a lacquer backing material is as follows:

25% to 35% by weight of solids and 75% to 25 65% by weight of solvents, the solids comprising about

100 parts by weight of nitrocellulose (4 seconds),

150 parts by weight of blown castor oil,

30 20 to 50 parts by weight of raw castor oil, and 100 to 150 parts by weight of ochre.

Blown linseed oil may be substituted for 75% of the blown castor oil, if desired. A preferred solvent comprises 55 to 65 parts by weight of ethyl 35 alcohol and 45 to 35 parts by weight (of parts by weight) of ethyl acetate.

Depending upon the quality of felt employed in the product of the present invention, the face of the goods may be wetted or moistened with a 40 heavy bodied linseed oil and "varnolene" mixture in various proportions either before or directly after applying the backing material or, in other words, before applying decorative material to the face of the sheet, as disclosed in my copending 45 application Serial No. 659,435 filed March 2, 1933. However, wetting the side of the sheet to which the decorative material is to be applied, generally weakens the appearance of the colors. From this standpoint, it is more advantageous to 50 apply oil or lacquer material merely to one side of the sheet, namely, the side opposite to which decorative material is applied.

Although oils and lacquers are mentioned for use in backing material, such materials as glue, 55 latex, casein, gums, and resins (artificial or natural) may also be used. Non-drying oils, as for instance castor oil, cottonseed oil, or pine oil, as well as drying oils may also be used. It is preferred to use such compositions as will reinforce 60 the sheet material without closing the pores, will bind the fibres together so that they will remain in the same relative position in the sheet when the sheet is flexed, and will have the desired adhesive properties for this purpose. Certain 65 materials that can be applied hot and that harden by cooling, as for instance, waxes or the like may be used. Also materials that can be applied in liquid form and that are hardened by chemical treatment may be used, as for instance, plastics of various kinds. If dyes are used for printing the display surface it is found highly desirable to use dyes or other material compatible therewith in the backing material. A pigmented 70 backing material gives a uniform appearance to the back of the sheet material and hides any 75

defects that might appear in the sheet or that might result from the printing of designs thereon.

The backing material applied to a sheet dries on the fibres of the sheet and increases their diameter thus decreasing the size of the voids between the fibres. The backing material thus tends to dam the flow of decorative coloring through the sheet from the display face or opposite side. If paints or other decorative coloring materials do penetrate through from the 10 face to the backing surface of the sheet, they do not pass through in such quantities as to result in a smearable appearance at the rear face. The colors of the decorated side of the sheet may be faintly or distinctly visible at the rear face depending on the amounts and nature of materials used for coloring and backing materials.

By first applying backing material to a fibrous sheet before passing it through the subsequent steps of the present process, the sheet is toughened in such a way that no cracks form by rolling. This is particularly true when lacquer is used as a backing material.

While the drawings, Figs. 2 to 4, indicate that the backing material penetrates a relatively short 25 distance it is to be understood that enough backing material may be applied to follow the fibres of a sheet a predetermined distance or all the way through from one side to the other. Heavy viscous paints used on print blocks generally 30 penetrate a less distance into a sheet than dyes or inks and therefore when the said paints are used enough backing material is applied to at least contact with the inner portions of the paint 35 layer in the sheet.

It is particularly to be noted that the use of the backing material must not close the space between the fibres within the sheet in such a way or to such an extent as to prevent the decorative material, applied from the opposite face, 40 from satisfactorily supplying decorative coloring not only on the surface but as deep down into the sheet or completely through to the back coating as may be desired. Such material as is applied to the rear face and extends perceptibly 45 into the sheet serves as a conditioner for the reception of decorative coloring applied to opposite face.

The invention has been disclosed herein for 50 illustrative purposes for making the product in its preferred embodiment, but it is to be understood that the scope of the invention is defined by the appended claims rather than by the foregoing description.

What I claim is:

1. A process of manufacturing decorative sheet material which process comprises applying a quick-drying, penetrating, oil-containing liquid to one side of a porous fibrous sheet material, controlling the amount of said liquid applied to 60 the sheet to effect penetration and avoid filling of the pores within the sheet, and applying decorative coloring material to the opposite side of the said porous sheet to permit penetration of the coloring material well down into the body 65 of the sheet after the oil-containing liquid has penetrated through the sheet part of the way.

2. A process of manufacturing decorative sheet material which process comprises applying oil-containing liquid to one side of a porous fibrous 70 sheet material, controlling the amount of said liquid applied to the sheet so that penetration is only part of the way but a substantial distance through the sheet, passing the resulting sheet to a print machine and maintaining a slack in 75

- the sheet to provide an interval for penetration of the said liquid and for conditioning of the sheet between the point at which the liquid is applied and the print machine, and applying decorative material to the opposite side of the porous sheet and permitting the decorative material to penetrate well down into the body of the sheet.
3. A process of manufacturing decorative sheet material which process comprises applying oil-
10 containing liquid to one side of a porous fibrous sheet material, controlling the amount of said liquid applied to the sheet so that penetration is only part of the way but a substantial distance through the sheet, drying the sheet while passing
15 it in slack formation to a print machine to provide an interval for penetration of the said liquid and for conditioning of the sheet, and applying decorative material to the opposite side of the porous sheet and permitting the decorative material to penetrate well down into the body of
20 the sheet.
4. A process of manufacturing decorative sheet material which process comprises applying oil-
25 containing liquid to one side of a sheet composed of chemically curled and swollen cellulose fibres, the said oil-containing liquid being applied to condition the sheet and promote rapid penetration of decorative coloring material into the body of the sheet when applied to the opposite side
30 thereof, drying the said sheet, and applying decorative coloring material to the opposite side of the said sheet.
5. A process of manufacturing decorative sheet material which process comprises applying quick-
35 drying oil-containing liquid to one side of a sheet composed of chemically curled and kinked cellulose fibres, controlling the amount of said liquid applied to the sheet so that there is uniform penetration only part of the way but a substantial
40 distance through the sheet, drying the said sheet, and applying decorative coloring material to the opposite side of the said sheet.
6. A process of manufacturing decorative sheet material which process comprises applying a sol-
45 lution of a drying oil in volatile solvent to one side of a fibrous sheet to effect rapid penetration of decorative coloring material directly into the body of the sheet when applied to the opposite side thereof, drying the said sheet, and applying decorative coloring material to the opposite side of the sheet.
7. A process of manufacturing decorative sheet material which process comprises applying a lacquer to one side of a fibrous sheet to effect rapid
55 penetration of decorative coloring material directly into the body of the sheet when applied to the opposite side thereof, drying the said sheet, and applying decorative coloring material to the opposite side of the sheet.
- 60 8. A process of manufacturing decorative sheet material which process comprises applying a quick-drying pigmented oil and solvent mixture to one side of a fibrous sheet, drying the said sheet while permitting penetration of the said
65 mixture a substantial proportion of the distance through the sheet, and applying decorative coloring material to the opposite side of the sheet.
- 65 9. A process of manufacturing decorative sheet material which process comprises applying a quick-drying pigmented lacquer to one side of a fibrous sheet while permitting penetration of the said lacquer a substantial proportion of the distance through the sheet, drying the said sheet, and applying decorative coloring material to the opposite side of the sheet.

10. A process of manufacturing decorative sheet material which process comprises applying lacquer to one side of a sheet composed of curly and kinky cellulose fibres to condition the sheet and promote rapid penetration of decorative coloring material directly into the body of the sheet when applied to the opposite side thereof, drying the said sheet while permitting penetration of the said lacquer a substantial proportion of the distance through the sheet, and applying decorative
10 coloring material to the opposite side of the sheet.
11. A process of manufacturing decorative sheet material which process comprises applying oil-containing liquid to one side of a fibrous sheet in sufficient amount to penetrate only part of the way but a substantial distance through the sheet thereby forming an oil-impregnated layer, and thereafter applying decorative paint material to the opposite side of the sheet in sufficient amount to penetrate into the sheet and contact with the oil-
15 impregnated layer within the body of the sheet.
12. A process of manufacturing decorative sheet material which process comprises applying lacquer to one side of a fibrous sheet in sufficient amount to penetrate only part of the way but a substantial distance through the sheet thereby forming a lacquer-impregnated layer, and thereafter applying decorative paint material to the opposite side of the sheet in sufficient amount to penetrate into the sheet and contact with the lacquer-
20 impregnated layer within the body of the sheet.
13. A process of manufacturing decorative sheet material which process comprises applying oil-
25 containing liquid to one side of a sheet composed of curly and kinky cellulose fibres in sufficient amount to penetrate only part of the way but a substantial distance through the sheet thereby forming an oil-impregnated layer, and thereafter applying decorative paint material to the opposite side of the sheet in sufficient amount to penetrate into the sheet and contact with the oil-
30 impregnated layer within the body of the sheet.
14. A process of manufacturing decorative sheet material which process comprises applying lacquer to one side of a sheet composed of curly and kinky cellulose fibres in sufficient amount to penetrate only part of the way but a substantial distance through the sheet thereby forming a lacquer-impregnated layer, and thereafter applying decorative paint material to the opposite side of the sheet in sufficient amount to penetrate into the sheet and to uniformly contact with the lacquer-
35 impregnated layer within the body of the sheet.
15. A process of manufacturing decorative sheet material which process comprises applying liquid material comprising at least one of a group including oil, lacquer, glue, latex, casein, gum, to one side of a porous fibrous sheet to condition it but not completely fill the spaces between the fibers, and applying decorative coloring material to the opposite side of the sheet thus conditioned.
16. A process of manufacturing decorative sheet material which process comprises applying a mixture containing oil and pigment to one side of a porous fibrous sheet to condition it but not completely fill the spaces between the fibres, and applying decorative coloring material to the opposite side of the sheet.
17. A process of manufacturing decorative sheet material which process comprises applying a liquid backing composition to one side of a porous fibrous sheet to condition it but not com-
75

pletely fill the spaces between the fibres, and then applying a decorative coloring material selected from a group comprising paints, dyes and inks, to the opposite side of the sheet.

5 18. A process of manufacturing decorative sheet material which process comprises applying a dye to a porous fibrous sheet to serve as a backing on one side of the said sheet, and applying dye materials for decorative purposes to the 10 opposite side of the said sheet.

15 19. A process of manufacturing decorative sheet material, which process comprises applying oil containing liquid to one side of a fibrous sheet material, controlling the amount of said liquid applied to the sheet so that penetration is only part of the way but a substantial distance through the sheet, applying a solution containing a drying oil to the opposite side of the sheet so as to moisten the fibres in the sheet and to penetrate well into said sheet, and immediately thereafter applying decorative coloring material to the opposite side 20 and causing it to penetrate the sheet therewith.

20. A process of manufacturing decorative

sheet material, which process comprises applying lacquer to one side of a fibrous sheet material, controlling the amount of said lacquer applied to the sheet so that penetration is only part of the way but a substantial distance through the sheet, 5 applying a solution containing a drying oil to the opposite side of the sheet so as to moisten the fibres in the sheet and to penetrate well into said sheet, and immediately thereafter applying decorative coloring material to said opposite side 10 and causing it to penetrate the sheet therewith.

21. A process of manufacturing decorative sheet material which comprises applying a liquid backing composition to one side of a porous fibrous sheet material in a regulated amount to effect 15 penetration into the body of the sheet while avoiding filling of the spaces between the fibers within the body of the sheet, and thereafter applying decorative coloring material to the opposite side of the said porous sheet to effect penetration of the coloring material well down into the body of the sheet. 20

JAMES J. JACKSON.
